UNITED STATES PATENT OFFICE.

LEMUEL N. DANTZLER, OF DALTON, GEORGIA.

DESIGN FOR A BACK-BAND LOOP.

SPECIFICATION forming part of Design No. 25,711, dated June 30, 1896.

Application filed May 16, 1896. Serial No. 591,885. Term of patent 7 years.

To all whom it may concern:

Be it known that I, LEMUEL N. DANTZLER, a citizen of the United States, residing at Dalton, in the county of Whitfield and State of Georgia, have invented and produced a new and original Design for a Back-Band Loop; and I do hereby declare the following to be a full, clear, and exact description of the same, reference being had to the accompanying drawings, forming a part thereof.

Figure 1 is a perspective view of a trace-holder attachment or loop for back-bands embodying my design. Fig. 2 is a section on the line $x x$, Fig. 1.

The leading feature of my design consists of the vertical loop and the transverse loop communicating with each other.

In the drawings, A designates the vertical loop, B the transverse loop, and C the opening of space connecting the loops. The top

D of the loop B crosses the central vertical plane of the loop A, and arms E complete the loop B in triangular shape. These arms stand out of the plane with the top D, at F, from whence the limbs H are bent in vertical position to form the loop A at right angles to and across the center of the loop B. Thus the top D, with its arms and limbs, incloses the loops and imparts a peculiar configuration of distinct and ornate effect.

What I claim is—

The design for a back-band loop substantially as herein shown and described.

In testimony whereof I affix my signature in presence of two witnesses.

LEMU^{EL} N. DANTZLER.
